HIS ATTORNEY.

Patented June 21, 1927.

UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

ROTATION MECHANISM FOR ROCK DRILLS.

Application filed June 26, 1926. Serial No. 118,737.

This invention relates to rock drills and more particularly to mechanism for rotating the drill steel.

The invention is of general application and possesses features of special advantage when applied to pneumatically operated drills of the hammer type in which reciprocation of the hammer piston is adapted to cause rotation of the drill steel in one direction of its travel.

One object of the invention is to rotate the drill steel effectively by means of a spirally fluted rifle bar and to effectively hold the pawls in engagement with the ratchet of the rifle bar. Another object of the invention is to simplify the construction of the ratchet mechanism and to eliminate breakable mechanical parts in order to increase the durability of the mechanism.

Other objects of the invention will be in part obvious and in part pointed out herein-after.

The invention will be more clearly understood by reference to the drawing, in which

Figure 1 is a longitudinal section through a hammer drill embodying the invention, and

Figure 2 is a cross section through the ratchet mechanism of the rotating device.

Referring to the drawings, the invention is shown as applied to a form of rock drill usually known as a drifter which is adapted to be mounted on suitable feeding mechanism (not shown) and is especially adapted for drilling holes in a generally horizontal direction. The drill comprises a reciprocating hammer piston A adapted to slide in a cylinder B. The type of drill here shown is of the so called valveless type in which the tail portion C of the piston A controls ports and passages for conducting motive fluid to either end of the cylinder B.

As is well known in the art, the exhaust of spent motive fluid is conducted to atmosphere through a piston controlled exhaust port D situated substantially at the center of the path of the piston A within the cylinder B. The tail portion C of the piston A is adapted to slide in a bore E of a flanged bushing F suitably attached at the rear end of the cylinder B. A head block G is provided, being mounted on the rear end of the flanged bushing F and having a suitable boss H at which a supply connection J for mo-

tive fluid of any suitable type may be attached.

A passage K in the head block G connects the supply pipe J with a suitable throttle valve L in the flanged bushing F for controlling the flow of motive fluid to a passage O leading to the bore E. Motive fluid to the front end of the cylinder B is supplied through a port P, a passage Q and a front cylinder port R. For driving the piston forward, motive fluid is admitted from the bore E to a passage S and a port T in the bore E controlled by the tail portion C of the piston A so that as the piston A moves backwardly or toward the head block G the port T is uncovered permitting motive fluid to flow past the neck U of the piston A into the rear end of the cylinder. In this type of tool the rear face of the tail portion C is constantly exposed to live motive fluid pressure since the bore E is constantly in communication with the supply of motive fluid through the throttle valve L.

In drilling with this type of drill, it is desirable that the drill steel be rotated in order not to jam in the hole being drilled. This is accomplished by means of a rifle bar V engaging a nut W fixed in the tail portion C of the piston A in a manner so that if the rifle bar be held stationary, the piston A will rotate. Preferably the rifle bar V is held against rotation on the up stroke of the piston A and permitted to rotate on the down stroke consequently the piston A is caused to rotate on its up stroke and permitted to move on its down stroke without rotation.

Rotation of the piston A is transmitted to a suitable drill steel X by means of a chuck Y provided with a nut Z engaging a fluted nose b of the piston A. The chuck Y being provided with a suitable bushing c of any desired form to engage the shank of the drill steel X. The cylinder B is also provided with a front cylinder washer d adapted to prevent the escape of motive fluid from the cylinder into the interior of the chuck. As the flutes of the piston nose b are drawn back past the cylinder washer d, motive fluid under pressure may then escape into the interior of the chuck Y and thence through the usual bore (not shown) of the drill steel X to blow the cuttings from the hole being drilled.

The rifle bar V is provided with a head e having ratchet teeth f which are adapted to be engaged by pawls g to permit rotation of the rifle bar V in only one direction. In 5 this manner reciprocation of the hammer piston A causes rotation of the hammer piston in engagement with the rifle bar V.

The rotation mechanism of which the rifle bar V forms a part includes a pawl ring h, shown more clearly in Figure 2, cut away as at j to admit the ratchet head e of the rifle bar and also to allow oscillation of the pawls g which are mounted in cylindrical holes k in the pawl ring h. The pawls g have in 15 most cases hitherto been pressed into engagement with the ratchet head e by means of spring pressed plungers mounted in a pawl ring somewhat similar to the pawl ring h. One disadvantage of the former practice 20 is that the springs wear and break very quickly.

By this invention the pawls are pressed into engagement with the ratchet head e by pressure of the motive fluid used for operating the piston A. To this end in this embodiment of the invention, the pawl ring h is provided with a plurality of bores o and counterbores p coaxial or in alignment with the bores o. Plungers q are provided 30 to operate in the bores o and to press against the pawls g. Each plunger q is provided with a shank r fitting closely in the bore o and a head s fitting accurately in the counterbores p. Motive fluid is supplied to the 35 counterbores p from the passage O in the flanged bushing F to a relatively small passage t in the flanged bushing F and a communicating passage u in the pawl ring h leading to an annular groove v in the periphery of the pawl ring. The annular groove v leads to the counterbores p.

As has been described above the bore E is constantly under pressure of live motive fluid when the throttle valve L is open. Motive fluid will therefore leak along the rifle bar V into the chamber formed by the cut away portions j in the pawl ring and pressure will therefore be exerted against the

projecting ends of the shanks r of the plungers q. The heads s of the plungers q 50 are however, of larger diameter than the shanks r and the fluid pressure tending to press the pawls g into engagement with the ratchet head e will therefore be greater than the pressure against the shanks r tending 55 to press the plungers out of engagement with the pawls g. Fluid under pressure is prevented from accumulating at the bottom of the counterbores p under the heads s of the plungers q by providing atmospheric 60 leak ports w leading through the head block G to atmosphere.

Preferably, the pawl ring h is clamped tightly between the head block G and the flange of the bushing F to prevent rotation 65 of the ring. A convenient construction for supporting the pawl ring h is shown in Figure 1 in which the head block G is counterbored as at x and the pawl ring h fits tightly 70 within the counterbore.

The drill in this instance is provided with a water tube y passing longitudinally through the head block G, the rifle bar V and the piston A from a water connection z in the head block G into the bore (not 75 shown) in the drill steel X.

Thus, by the above construction are accomplished among others the objects hereinbefore referred to.

I claim:

A rotation mechanism for percussive drills comprising a rifle bar having a ratchet head, a pawl ring surrounding said ratchet head, pawls to engage said ratchet head and supported by said pawl ring, bores and counterbores concentric in said ring, differential piston plungers in said bores and counterbores to actuate said pawls, atmospheric leak ports at the bottom of said bores to relieve fluid pressure under the heads of said piston 90 plungers, and a circumferential groove in said pawl ring in communication with a source of constant pressure.

In testimony whereof I have signed this specification.

CHARLES C. HANSEN.
